United States Patent Office.

CHARLES R. SHERMAN AND WENDELL MACY, OF NEW BEDFORD, MASSACHUSETTS.

Design No. 3,909, dated March 15, 1870.

DESIGN FOR THERMOMETERS.

The Schedule referred to in these Letters Patent and making part of the same.

To all whom it may concern:

Be it known that we, CHARLES R. SHERMAN and WENDELL MACY, of New Bedford, in the county of Bristol, and State of Massachusetts, have originated and designed a new Pattern for Thermometers, of which the following is a full, clear, and exact description, reference being had to the accompanying drawing making part of this specification, in which—

A is the thermometer, having the plate bent in semi-cylindrical form.

B, ornamental cross, of wood or other suitable material, forming the back or support of thermometer.

Claim.

What we claim as our invention, and desire to secure by Letters Patent, is—

The design or pattern for thermometers herein set forth.

C. R. SHERMAN.
WENDELL MACY.
